(57) **CLAIM**

The ornamental design for a livestock prod, as shown and described.

DESCRIPTION

FIG. 1 is a front view of the livestock prod, showing my design;

FIG. 2 is a rear view thereof;

FIG. 3 is a top view thereof;

FIG. 4 is a bottom view thereof;

FIG. 5 is a right view thereof, shown enlarged for clarity of disclosure;

FIG. 6 is a left view thereof, shown enlarged for clarity of disclosure;

FIG. 7 is a magnified top left perspective view of the livestock prod, shown enlarged for clarity of disclosure;

FIG. 8 is an enlarged front view of detail “8” of FIG. 1; and,

FIG. 9 is an enlarged top view of detail “9” of FIG. 3. The portions of the design that are in dashed lines are for illustrative purposes only and do not form part of the claimed design.

1 Claim, 6 Drawing Sheets
